UNITED STATES PATENT OFFICE.

SIGMUND STERNAU, OF NEW YORK, N. Y.

DESIGN FOR A KETTLE.

SPECIFICATION forming part of Design No. 23,987, dated February 5, 1895.

Application filed October 6, 1894. Serial No. 525,175. Term of patent 3½ years.

To all whom it may concern:

Be it known that I, SIGMUND STERNAU, a citizen of the United States, residing in New York, county of New York, and State of New York, have invented and produced a new and original Design for Kettles, of which the following is a specification, reference being had to the accompanying drawing, which shows the kettle in perspective.

10 The leading or characteristic feature of my design is the kettle body ornamented as shown and having the fanciful handle extending upwardly therefrom, and a comparatively small and shallow base downwardly therefrom.

15 A is the kettle body, having the outline or contour shown, and ornamented as at a, a. From the side of the body extends the ornamented spout B, and from the lower side the comparatively small and shallow base C. From the upper side of the body A extends 20 the handle D curved and ornamented as shown.

E is the ornamented top or cover.

What I claim is—

The design for a kettle as hereinabove 25 shown and described.

SIGMUND STERNAU.
